CLAIM

The ornamental design for a short tire brush, as shown and described.

DESCRIPTION

FIG. 1 is a perspective view of a short tire brush;
 FIG. 2 is a left side elevational view of the short tire brush;
 FIG. 3 is a right side elevational view of the short tire brush;
 FIG. 4 is a rear side elevational view of the short tire brush;
 FIG. 5 is a front side elevational view of the short tire brush;
 FIG. 6 is a top plan view of the short tire brush; and,
 FIG. 7 is a bottom plan view of the short tire brush.
 The broken lines represent portions of the short tire brush,
 and form no part of the claimed design.
